[57] CLAIM

The ornamental design for a bottle, as shown and described.

DESCRIPTION

FIG. 1 is a front elevational view of the bottle showing my new design, the rear elevational view being a mirror image;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front elevational view of a second embodiment of the design of FIG. 1, the only difference being a decrease in height;

FIG. 7 is a top plan view of FIG. 6;

FIG. 8 is a front elevational view of a third embodiment of the design of FIG. 1, the only difference being a decrease in height and width;

FIG. 9 is a top plan view of FIG. 8.
